CRATE

Frank J. Krzyzak, Chicago, Ill., assignor to
Republic Box Company, Chicago, Ill., a cor-
poration of Illinois

Application July 2, 1932, Serial No. 620,579

3 Claims. (Cl. 217—20)

The present invention relates to crates to be used in transporting milk bottles and the like of the type in which there is a reticulated bottom upon portions of which bottles are supported while other portions of the bottom brace the portions upon which the bottles are supported and give rigidity thereto.

One object of this invention resides in the improved manner of mounting the rods upon which the bottles are mounted.

Another object of this invention resides in an improved method whereby the rods which support the bottles may be carried by members held in rabbeted portions in the end boards of the crate instead of being arranged between adjacent boards.

Another object of this invention resides in attaching the rods which support the bottle to metallic strips which thereafter are riveted to the end boards of the crate and form a strong structure which is prevented from warping and shrinking to a great extent and in which the supports for the rods are firmly held in place.

Other objects of this invention will appear hereinafter as the description thereof proceeds, the novel features, arrangements, and combinations being clearly set forth in the accompanying claims.

In the drawings:

Fig. 1 is a perspective view of a crate embodying my invention, parts thereof being broken away and omitted for the sake of clearness;

Fig. 2 is a perspective view of the assembly of the end boards and grid-work forming the bottom of the crate;

Fig. 3 is a horizontal section taken substantially along the line 3—3 of Fig. 1;

Fig. 4 is a fragmentary sectional view taken just above the bottom boards of the assembled crate;

Fig. 5 is a perspective view of the bottom of a modified form of crate embodying my invention;

Fig. 6 is a view similar to Fig. 4 of the modifications of the invention shown in Fig. 5; and

Figs. 7 and 8 are fragmentary detail views showing the details of the form of the invention shown in Fig. 6.

The crate constructed according to my invention has four walls, including two end walls and two side walls. The end walls comprise the bottom end boards 10, center end boards 11, and top end boards 12, the latter having hand holes 13 therein to enable one to lift the crate. The sides of the crate comprise the bottom side boards

14, center side boards 15, and top side boards 16 each superimposed upon each other. Angle irons 17 are arranged in suitably rabbeted corners 18 of the end boards 10, 11, and 12, and the side boards have their ends arranged within the angle of the angle iron as is clearly illustrated in Fig. 1.

The crate has two separators, a lower separator 19 and an upper separator 20 each composed of a plurality of metal strips arranged in crossed relation and in rectangular formation, the ends of the strips being nailed to the side boards and the end boards. As shown in the drawings, the strips which are nailed to the end boards are nailed to the center end boards 11 from the top and the bottom, whereas the strips of the lower separators 19 which are attached to the side boards are attached to the bottom side boards, and the strips of the upper separator are nailed to the center side boards as will be seen from an inspection of Fig. 1. Dowels 21 are interposed between adjacent boards so as to hold the boards in vertical alignment with each other.

This invention is particularly concerned with the bottom construction of the crate. The bottom construction is perhaps best illustrated in Figs. 2, 3, and 4. In these figures, 22 represents metal strips or plates which extend the full length of the end boards 10 and each of these strips has a plurality of off-set portions 23 for purposes which will appear presently. The ends 24 of these strips extend into the rabbeted corners 18 and are counter-sunk below the surface of the rabbeted portion 18, as is clearly illustrated by dotted lines in Fig. 3 so that when the angle irons 17 are placed in the rabbeted portions 18, the angle irons will contact with the surfaces of the rabbeted portions and also with the surface of the metal strips, whereby the ends of the strips 22 are maintained between the angle iron and the end boards. When the side bottom boards 14 are put in place to hold the angle irons, the bottom side boards prevent the ends of the strips 22 from moving toward each other in the direction of the length of the crate. These strips are riveted at intervals to the crate by the rivets 25, the outer ends 26 of which are counter-sunk below the outer surface of the crate and are provided with washers 27 to prevent the rivets from imbedding themselves too deeply into the wood. Each of

the off-set portions 23 is perforated to receive the end of one of the rods 28 which extend parallel to the longitudinal dimension of the crate, which rods support the bottles inserted in the openings provided in the separators 19 and 20.

The ends of the rods are upset as at 29 so as to prevent separation of the rods 28 and strips 22. The rods 28 may be preformed with upset heads at one end; then threaded through the perforations in the off-set portions 23 of one strip; then through openings in the flanges of the channel shaped bracing members 20, and finally through the other strip 22. After this has been done, the other ends of the rods are upset so as to retain the members 22 and 33 and 28 in assembled relation with respect to each other.

The channel shaped bracing members 30 are provided with ears 31 perforated to receive fastening means. The ears 31 are arranged in the rabbeted portions 32 of the bottom side members 14, and nails are driven through the bottom of the side members 14 and through the perforations in the ears to hold the ears in place within the rabbets 32. This prevents the bottom side members from spreading and also serves as supports for the bracing members 30 which in turn support the rods 28 at spaced intervals in their length. It will be understood that the rods 28 are upset at their ends in such a manner that the strips 22 when moved outwardly along the rods to their outermost limits are spaced from each other slightly less than the space between the bottom end boards when the crate is assembled. The strips 22 are riveted to the end boards 10 and then after the end members 11 and 12 are superimposed upon the end members 10, the ends of the crate are stretched in a stretching machine to place the rods 28 under tension so that they will not vibrate and so that the tension will assist in supporting the bottles.

In Figs. 5, 6, 7, and 8, I have shown a modified construction in which the rods instead of being connected to a continuous metal strip as in Figs. 1 to 4 inclusive, are connected to end plates 33 having perforations 34 therein for the reception of a suitable fastening means such as a nail. These plates are inserted in the rabbets 35 and are provided with lugs 36 to limit the amount that these plates can be moved into the rabbets 35. After the plates have been inserted in the rabbets, the same are secured by means of nails 37 or the like which pass through the end boards 38 and the perforations 34 in the plates 33. Before the plates are connected to the end boards 38, the rods 39 are passed through perforations in the ears 40 on the strips or plates 33 and hooked over as at 41 to form a loop to prevent the separation of the plates and rods. Channel shaped bracing strips 42, similar to the strips 30 in Figs. 1 to 4 inclusive, are arranged on the rods in the same manner as in the first modification described. After the plates 33 have been inserted in the rabbets 35 and secured in place by the nails 37, and the remaining portions of the ends of the crate are superimposed on the members 38, the ends are stretched the same as previously described and the angle irons 43 inserted in the rabbets 44 of the end pieces, and the bottom side pieces 45 inserted there-between as previously described in connection with the bottom side boards 14. Lugs 36 prevent the plates 33 from moving into the rabbets 35 more than desired, and also act as means for gauging the position within the rabbets of the holes 34 which are to receive the nails so that the nails can be driven through the wood and through the

perforations by special locating machinery or the like. The rest of the crate is formed in the same manner as described in connection with Figs. 1 to 4 inclusive.

In Fig. 7, I have shown a still further modification of the invention in which the end board is composed of two strips 46 and 47, one of which, preferably the strip 46, has a recess 48 which forms with the strip 47 an opening which is the full equivalent of the rabbet 35 shown in Fig. 5. The strips 47 and 46 may be secured together after the recess 48 is formed or after the plate 33 is in operative position. The strips are also of course secured to the angle irons in the usual manner.

Obviously those skilled in the art to which this invention pertains may make various changes in the modifications of the invention which I have disclosed without departing from the spirit of this invention, and therefore I do not wish to be limited except as hereinafter set forth in the appended claims.

I claim:

1. In a crate, the combination with a frame comprising side members and end members, said end members being recessed to receive the side members, a metal strip secured to each end member and running longitudinally of said end member from one side of said crate to the other with portions thereof arranged within said recesses and between the bottom of said recess and the side pieces which are arranged in said recess, whereby the ends of said strips are securely held in place and prevented from movement in the general direction of the length of said side pieces, said metal strips having openings therein for receiving supporting rods, and rods arranged with their opposite ends in openings in the strips at opposite ends of said crate.

2. In a crate, the combination with a frame comprising side members and end members, said end members being recessed to receive the side members, a metal strip secured to each end member and running longitudinally of said end member from one side of said crate to the other with portions thereof arranged within said recesses and between the bottom of said recess and the side pieces which are arranged in said recess, whereby the ends of said strips are securely held in place and prevented from movement in the general direction of the length of said side pieces, said metal strips having openings therein for receiving supporting rods, and rods arranged with their opposite ends in openings in the strips at opposite ends of said crate,

3. In a crate having side and end members, the end members being formed with spaced recesses at their opposed marginal edges and said side members having end edges received in said recesses, metal strips extending each along one of said side members, the opposed ends of each strip being received each in a recess and secured between a recessed surface of a said end member and an end of a side member, and a rod extending within the crate between and secured to the metal strips on opposite sides of the crate.

FRANK J. KRZYZAK.
